MUFFLER JACK

Joseph J. Mizer, Racine, Wis., assignor to Walker Manufacturing Company of Wisconsin, Racine, Wis., a corporation of Wisconsin

Application August 18, 1941, Serial No. 407,330

3 Claims. Cl. (29—239)

The present invention relates to a device for separating telescoped members, and is particularly adapted for use in separating exhaust pipes and tail pipes from the mufflers of internal combustion engines.

Due to the high temperatures, the corrosive gases, and the presence of water vapor in the exhaust gas in internal combustion engines, the telescopic joints between exhaust pipes and tail pipes and mufflers become so badly corroded that it is frequently exceedingly difficult to separate the parts for repair and replacement purposes. This difficulty is further enhanced by the relative inaccessibility of mufflers, exhaust pipes and tail pipes in motor vehicles. As a result, attempts to separate these elements frequently result in the destruction of an otherwise satisfactory part of the exhaust system of the motor vehicle.

It is the object of the present invention to provide an exceedingly simple, inexpensive and practical device, which may be designated a muffler jack, for the purpose of exerting a very high direct line pulling force to separate a muffler from either its exhaust pipe or tail pipe.

A further object of the invention is to provide a device of the type mentioned which is adapted for use on a majority of motor vehicles and which is designed to permit use where the parts to be separated are relatively inaccessible.

Other objects and advantages of the invention will become apparent from the following specification, the accompanying drawings, and the appended claims.

In the drawings, in which like numerals are used to designate like parts in the several views throughout:

Figure 1 is a fragmentary side elevation of a muffler and tail pipe, illustrating the manner in which the improved device of the present invention is utilized;

Fig. 2 is an enlarged view of the principal parts of the device, or muffler jack;

Fig. 3 is an elevation of the device shown in Figure 2, taken at right angles to Figure 2;

Fig. 4 is a view similar to Figure 2, showing a modified form of the invention;

Fig. 5 is an elevation of the modified form shown in Figure 4, taken at right angles to the view shown in Figure 4;

Fig. 6 is a front elevational view, partly in section, showing the form of clamp utilized in connection with the device;

Fig. 7 is a side elevation of the clamp;

Fig. 8 is a section taken on the line 8—8 of Figure 6;

Fig. 9 is a view of the ratchet handle forming a part of the device; and

Fig. 10 is a view of the ratchet element incorporated in the handle illustrated in Figure 9.

As indicated in Figure 1, a conventional tail pipe 10 in an internal combustion engine exhaust system is secured to the muffler 11 by telescoping the tail pipe 10 into a split sleeve 12 fixed to the end 13 of the muffler. When the parts are initially assembled, a removable holding strap, not shown, embraces the split sleeve 12 and clamps the sleeve upon the tail pipe 10. A similar connection is utilized between the muffler and the exhaust pipe, and the present invention is equally adapted for use in separating either connection. When it is desired to remove either the exhaust pipe or the tail pipe from the muffler, the holding strap is removed and the parts are separated by direct axial pulling movement. In actual practice, as a result of what is frequently termed "a corrosion weld," which forms between the telescopic pipe 10 and sleeve 12, it is exceedingly difficult to separate the pipe and muffler, and attempts to do so frequently result in destruction of one or both of these elements.

The preferred form of mechanism embodying the present invention, which is best illustrated in Figures 1, 2 and 3, comprises a specially designed scissors jack mechanism comprising a plate 14 having a slot 15 formed in its upper edge. The slot 15 is of sufficient width and depth to receive and embrace the tail or exhaust pipe and the attaching sleeve of the muffler. In actual practice, motor vehicle exhaust and tail pipes vary in size from approximately one and a half inches to two and a half inches in diameter, and the slot 15 in the plate 14 is preferably made sufficiently wide and deep to receive the largest size of pipe.

The scissors mechanism, itself, is formed of four identical levers. Of these four levers, one pair of levers 16 and 17 are pivotally secured at one end by means of rivets 18 and 19 to angle brackets 20 and 21, which, in turn, are welded or otherwise secured, respectively, to the plate 14 at opposite sides of the slot 15. The axes of the rivets 18 and 19 are aligned to permit the levers 16 and 17 to swing as a unit. The second pair of levers 24 and 25 are pivoted intermediate their ends to a corresponding point on the levers 16 and 17, respectively, by means of a spacer member 26, which extends between the levers 24 and 25 and is provided at its ends with trunnions 27 and 28 extending through suitable aligned openings in the four levers.

The opposite ends of the lever 16 are secured

together by means of a cylindrical spacer 30, which is pivotally secured to the levers by means of trunnions 31 and 32. The opposite ends of the levers 24 and 25 are similarly secured together by a partially cylindrical spacer 34 having trunnions 35 and 36 extending through suitable aligned openings in the levers 24 and 25.

The spacer member 30 is provided with a screw threaded opening, through which is threaded a screw element 38. The right-hand end of the screw 38, as viewed in Figure 2, is provided with a reduced trunnion 39 journalled for rotation in a suitable opening in the spacer 34. The shoulder formed on the screw by the reduced end portion 39 seats against a flat surface 40 formed on the spacer 34 to form an axial thrust bearing. The end of the trunnion 39 is riveted over at 41 to retain the trunnion 39 within the opening in the spacer 34.

It will be obvious that as a result of the mechanism so far described, rotation of the screw 38 will cause the two pairs of levers to pivot relative to each other about the aligned trunnions 27 and 28. In order to effect such rotation of the screw 38, the end thereof is provided with a hexagonal shank 44 adapted to receive a specially designed ratchet handle indicated generally at 46 in Figure 1 and hereinafter described in further detail.

In use, it will be apparent that the plate 14 is fitted over the tail pipe 10 or sleeve 12 and seated against the end 13 of the muffler 11 to provide an axial thrust support for the jack mechanism. The free ends 48 and 49 of the levers 24 and 25 are spaced apart sufficiently to embrace the tail pipe 10, and they are adapted to engage a specially designed clamp, indicated generally at 50 in Figure 1, which is fixed upon the tail pipe 10.

The clamp 50, as best shown in Figures 6, 7 and 8, is formed of two approximately semi-circular clamping elements 52 and 53, which are secured together by bolts 54 and 55 in such a way that tightening of the bolts increases the clamping pressure of the two clamping portions upon the tail or exhaust pipe. The bolts 54 and 55 are provided with hex headed nuts 56 and 57, respectively, which are preferably of the same size and shape as the end portion 44 of the screw 38, in order that the ratchet handle 46 may fit both the nuts and the stem 44 of the screw.

It will be noted, as best shown in Figures 6 and 8, that the clamping elements 52 and 53 are specially constructed to exert a maximum gripping action on the pipe to prevent any axial slippage during operation of the jack mechanism. For this purpose, the inner surfaces of the clamping elements, which surfaces engage the pipe, are recessed, as best shown in Figure 8, to provide annular ridges, or knife edges, 58 and 59 at each side of the clamp adapted to dig in or embed slightly in the tail pipe and have a positive gripping action. The ridges 58 and 59 are preferably formed as segments of a circle whose diameter is equal to the largest diameter of the pipe to which the clamp will be applied. It will be noted, as shown in Figure 6, that when the clamp is used on smaller pipes a gripping action is further enhanced by reason of the fact that the knife edges 58 and 59 engage only a limited portion of the periphery of the pipe.

The ratchet handle, which may be used to operate the screw 38 as well as to tighten the nuts 56 and 57 of the clamp, is shown in detail in Figures 9 and 10. The ratchet handle, or wrench, comprises a ratchet wheel 60 fixed to a generally

tubular member 61 having an axial hexagonal socket 62 adapted to fit the shank 44 of the screw 38 as well as the nuts 56 and 57. A pair of side plates 63 and 64 are journalled on the tubular member 61 and pivotally support a handle 65 by means of a rivet 66 passing through the side plates 63 and 64 and the handle 65. Pivotal movement of the handle 65 with reference to the side plates 63 and 64 is limited by a slot 67 formed in the handle and adapted to receive a rivet 68 fixed to and extending between the side plates 63 and 64. Slot 67 so limits the pivotal movement of the handle relative to the side plates that in one extreme position, illustrated in Figure 9, a dog 69, formed on the end of the handle, will operatively engage one of the ratchet teeth; whereas, in the opposite extreme position of the handle relative to the side plates 63 and 64, the dog 69 will be entirely disengaged from the ratchet.

As a result of this arrangement, upon movement of the handle 65 counterclockwise, as viewed in Figure 9, the dog 69 will engage with the ratchet teeth and cause rotation of the ratchet and the socket sleeve 61. When the handle 65 is moved in the opposite or clockwise direction, the dog 69 will disengage from the ratchet teeth and no movement of the ratchet wheel or sleeve 61 will occur. The use of a ratchet handle or wrench for the purpose of operating the screw 38 or the nuts 56 and 57 is of advantage in view of the limited space available to operate the mechanism beneath a motor vehicle.

The mode of use of the preferred form of the invention shown in Figures 1, 2 and 3 is believed to be obvious from the illustration in Figure 1. Clamp 50 is secured in position, as shown, and the plate 14 is simply seated against the end 13 of the muffler 11 and pushed upwardly until the pipe 10 or sleeve 12 seats in the bottom of the slot 15. This positively locates the mechanism in the proper plane and in a position embracing the pipe 10 and sleeve 12.

It is important, in order to produce a straight line pulling force, that the free ends 48 and 49 of the levers 24 and 25 engage the clamp 50 on diametrically opposite sides of the pipe 10 as closely as possible. Accordingly, if the pipe 10 and sleeve 12 are relatively small in diameter, it may be necessary to let the supporting plate 14 drop down slightly until this condition is achieved. Before placing the mechanism in position, the scissors mechanism should be collapsed as far as possible and the clamp 50 should be placed as close as possible to the muffler, leaving only sufficient room to insert the collapsed scissors mechanism. When the parts are in position, the ratchet handle 46 is simply operated to expand the scissors mechanism and exert a pushing force in opposite directions upon the muffler and clamp 50. It is possible, with the mechanism shown, for an ordinary workman to exert force in the neighborhood of one thousand pounds, which is adequate to separate the exhaust or tail pipe from the muffler under all ordinary conditions.

While the use of the plate 14 is of a great advantage in assisting the workman in locating the mechanism in proper position and in supporting the mechanism in use, it can be omitted and the jack mechanism constructed as shown in Figures 4 and 5. In this modified form, the mechanism is identical to that previously described except that the angle brackets 20' and 21', which are pivoted by means of rivets 18' and 19' to the

upper ends of the levers 16' and 17', are intended to directly engage the end 13 of the muffler 11.

This modified form of the invention, as illustrated in the drawings, also incorporates a further feature in that the upper ends of the links 24' and 25', instead of directly engaging the clamp, are provided with angle brackets 10 and 11, respectively, which are pivotally secured to the levers by means of rivets 72 and 73. The angle brackets 10 and 11 provide flat surfaces of increased area to engage the clamp 50. It will be apparent that a similar arrangement of angle brackets may be utilized in connection with the form of invention shown in Figures 1, 2 and 3, if desired.

While only two forms of the invention are shown and described, it will be apparent that various modifications of the details of construction may be resorted to without departing from the spirit of the invention or the scope of the appended claims.

What is claimed is:

1. A device for separating telescoped elements, comprising a pair of substantially parallel levers secured together at one end, a second pair of substantially parallel levers secured together at one end, the levers of each pair being pivoted intermediate their ends to the levers of the other pair, respectively, to form a scissors linkage, means connected between the ends of the pairs of levers which are secured together for varying the distance between said ends of the two pairs of levers, the opposite ends of said levers being spaced apart so that said device may freely be fitted over said tube from the side thereof and being adapted to embrace the telescoped elements and engage axial thrust sustaining surfaces on said members at diametrically opposite sides of said members.

2. In a device for forcibly separating an ex-

haust muffler from a tube telescoped with respect thereto, a plate having a slot in one edge of a width and depth sufficient to receive and embrace said tube with the plate engaging the end of the muffler at diametrically opposite sides of the tube, a pair of substantially parallel levers pivoted on a common axis to said plate at opposite sides of said slot, an element pivotally secured to and between the opposite ends of said levers on an axis parallel to said first mentioned axis, a second pair of substantially parallel levers pivoted, respectively, to the levers of the first pair intermediate the ends of the levers to form a scissors linkage, said second pair of levers at one end being spaced apart and adapted to embrace said tube and operatively engage axial thrust sustaining surfaces thereon at diametrically opposite sides of the tube, an element pivotally secured to and between the opposite ends of the second pair of levers on an axis parallel to the aforementioned axes, and a jack mechanism connected to and between said elements.

3. In a device for forcibly separating an exhaust muffler from a tube telescoped with respect to said muffler, a scissors linkage including a pair of lever structures pivoted together intermediate their ends, means connected between the end of one lever structure and the corresponding end of the other lever structure for pivotally swinging said structures relative to each other, the opposite end of one of said lever structures being pivotally secured to a plate having a slot in one edge adapted to receive and embrace said tube, said plate being adapted to engage the end of said muffler at diametrically opposite sides of the tube, the opposite end of the other lever structure being adapted to embrace the tube and operatively engage thrust sustaining surfaces on said tube at diametrically opposite sides of said tube.

JOSEPH J. MIZER.
